(57) **CLAIM**

The ornamental design for a two-way disc mailer, as shown and described.

DESCRIPTION

FIG. 1 is a perspective view of a two-way disc mailer of our new design, where the horizontal, heavy solid interior line is a fold line, not surface ornamentation, the stippled, horizontal stripes are each a layer of adhesive, the horizontal, dashed lines are perforations, and the phantom text forms no part of the claimed design;

FIG. 2 is a plan view of FIG. 1 with the two-way disc mailer in a flat configuration, where the horizontal, heavy solid line is a fold line, not surface ornamentation, the stippled, horizontal stripes are each a layer of adhesive, the horizontal, dashed interior lines are perforations, and the phantom text forms no part of the claimed design;

FIG. 3 is a right-side view of FIG. 1 with the two-way disc mailer in a flat configuration, the left side view being a mirror image thereof;

FIG. 4 is a bottom view of FIG. 1 with the two-way disc mailer in a flat configuration;

FIG. 5 is a top view of FIG. 1 with the two-way disc mailer in a flat configuration; and,

FIG. 6 is a perspective view of the two-way disc mailer of FIG. 1 in a fully closed configuration.
